Forrest L. Stotler, Akron, Ohio, assignor of one-half to Bruce S. Blake, Akron, Ohio

Application June 21, 1938, Serial No. 77,967

Term of patent 7 years

To all whom it may concern:

Be it known that I, Forrest L. Stotler, a citizen of the United States, residing at Akron, in the county of Summit and State of Ohio, have invented a new, original, and ornamental Design for a Swing, of which the following is a specification, preference being had to the accompanying drawing, forming part thereof.

Figure 1 is a side elevation of the swing.
Figure 2 is an end elevation of the swing.
Figure 3 is a plan view of the swing.

I claim:

The ornamental design for a swing, as shown.

FORREST L. STOTLER.
